ATTORNEY.

UNITED STATES PATENT OFFICE

FREDERICK L. RE QUA, OF SAN FRANCISCO, CALIFORNIA

RAILWAY RAIL JOINT

Application filed October 3, 1930. Serial No. 486,133.

This invention relates to improvements in railway rail joints.

The principal object of the invention is to prevent the disintegration of rail ends.

5 Another object is to reduce and distribute the resistance or impact force of rolling stock passing over rail joints.

Another object is to eliminate the traction wave in the tread of the rail adjacent its ends.

10 Other objects and advantages will appear as the description progresses.

The rolling and pounding action of rolling stock in passing along the tops of railway rails, whether welded or hardened or not, 15 tends to elongate the tread portion. This causes a burr to curl over the ends of the rails at each joint. When the rails expand under sun temperature the ends abut each other. As the wheels on a rail approach the 20 end of the rail, that end is depressed below the level of the end of the next following rail. If the opposing burrs overlap, one or both of them are eventually dislodged by the rise and fall of the rail ends under the weight of 25 traffic, as described.

The elongation of the tread portion tends to harden and stratify it longitudinally, causing it to become scaly. When these end burrs are dislodged, as stated, they pry 30 up a portion of the contiguous tread, leaving the top surface of the rail rough and pitted.

The wheels of succeeding rolling stock thereafter drop into these fracture pits and 35 in leaving them, bounce away and again strike the rail some little distance beyond. A wave or depression is thus formed in the rail tread several inches from the mutilated end. This condition in turn becomes causative, so 40 that following an initial surface fracture the rail end rapidly depreciates and becomes unsafe in a relatively short time, due to crystallization of the metal of the rail. This results in impact wear on wheels and rapid wear on 45 the joint bars and bolts. In addition the severe vibration occasioned by passing trains has an enhanced tendency to loosen the nuts on the joint bar bolts.

It has been common practice to variously 50 bevel the ends of the rails where they meet

in the joint to form a transverse notch in the track, so that when the ends of the rails are forced together by expansion the tread portions do not contact. This notch prevents the disruption due to the dislodgment of the 55 burrs, but it does not prevent the formation of the burrs nor the impact shock when the wheels hit the high rail ends, which it is one of the objects of this invention to accomplish.

In this specification and the accompanying drawings the invention is disclosed in its preferred form. But it is to be understood that it is not limited to this form because it may be embodied in other forms. It is 60 also to be understood that in and by the claims following the description it is desired to cover the invention in whatsoever form it may be embodied.

In the one sheet of drawings:

Fig. 1 is a side elevation diagrammatically illustrating one conventional form of notched track.

Fig. 2 is a similar view of a modified form of notch.

Fig. 3 is a notched rail joint operating under the usual conditions to be found in practice, the condition being slightly exaggerated to better illustrate the effect.

Fig. 4 is a similar view of a rail end diagrammatically illustrating the effect of traffic on any rail end held in an inefficient rail joint, with the resultant burr and traction waves caused by traffic.

Fig. 5 is a view similar to Fig. 3 illustrating the advantages of this invention, under comparative conditions.

The method and construction of the present invention are best illustrated in Fig. 5, wherein the two alined rail ends 1 and 2 are 90 spaced apart the required expansion distance 3. These ends are joined by any suitable form of joint or fish plates 4—4 fitting between the rail heads and bases 5—6 and drawn together by the transverse bolts 7—7.

The disadvantages of the forms shown in Figs. 1, 2, 3, 4 are largely the result of the sharp angles at 8 which present no inclined angle of approach for the wheel 9. In consequence the blow struck by the wheel 100

amounts to several tons of impact concentrated at the apex 8. Such a condition, especially as in Fig. 3, rapidly upsets the end of the rail tread, see Fig. 4, forming the hump 10 which causes the wheel to jump upward and descend at about the point 11 with another concentrated impact which gradually forms a depression in the rail tread, as explained above. Traffic being sometimes in both directions, both ends of the rails soon present this mutilation, so that the track adjacent the rail end becomes a succession of traction waves as indicated, the disadvantages of which are sufficiently manifest.

All of these disadvantages are eliminated by modifying the rail ends with an arcuate chamfer 12, as shown in Fig. 5. The ductile tread of the rail "flows" into the arc at 12 without forming an overhanging burr as at 13.

The incline plane presented by the segment at 12 causes the wheel 9 to depress the higher rail end 1, without the reacting rebound and "jumping" previously described; thus very simply eliminating the many disadvantages of the angular notches 8 above described.

The simplicity of this arcuate chamfer 12 is out of all proportion to the many advantages following its application in this art.

This chamfering is very easily accomplished by a portable shaper or grinding wheel clamped to the track at the rail joints.

Having thus described this invention what I claim and desire to secure by Letters Patent is:

1. A rail joint with the abutting rail ends arcuately chamfered transversely of their tread portions.
2. A rail joint with the tread portions of the rails curved downwardly at their abutting ends.

In testimony whereof I have hereunto set my hand this 29th day of September, 1930.

FREDERICK L. RE QUA.
